CLAIM

The ornamental design for a pet feeder tilted table, as shown and described.

DESCRIPTION

FIG. 1 illustrates a perspective view of a pet feeder tilted table when in use;

FIG. 2 illustrates a perspective view of the pet feeder tilted table;

FIG. 3 illustrates a front view thereof;

FIG. 4 illustrates a rear view thereof;

FIG. 5 illustrates a right side view thereof;

FIG. 6 illustrates a left side view thereof;

FIG. 7 illustrates a top view thereof; and,

FIG. 8 illustrates a bottom view thereof.

The broken lines showing of a pet bowl in FIG. 1 is for illustrative purposes only and forms no part of the claimed design.
